TWEEZERS ACTUATING DEVICE

Joseph Drabik, Chicago, Ill.

Application July 1, 1946, Serial No. 680,545

2 Claims. (Cl. 81—43)

1

The present invention relates to tweezers and has for its main object the provision of means for maintaining the jaws in tweezers in their mutual adjusted relation.

Tweezers used for grasping and lifting small objects such as watch screws, nuts, etc. oftentimes are inefficient due to lack of means to maintain the jaws of the tweezers in a rigid contacting relation with the object grasped thereby. When tweezers are used as a tool to manipulate small objects such as watch screws for the purpose of affixing the same within a watch, the same is liable to be disengaged from tweezers during the process of operation. Therefore, a further object of the present invention is the provision of means in tweezers for maintaining the jaws thereof in a frictional, disengageable contact until the operation of tweezers upon the object held is completed.

A still further object of the present invention is the provision of adjustable means for the jaws of tweezers for adapting the same for use as calipers.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application, and in which like designating characters refer to corresponding parts throughout the several views:

Fig. 1 is a top elevational view of the tweezers, with a knob in association with one jaw of tweezers for operating the adjusting mechanism for adjusting the jaws in tweezers;

Fig. 2 is a side elevational view of the tweezers;

Fig. 3 is a longitudinal cross-sectional view through the tweezers showing the adjusting mechanism in an inoperative position;

Fig. 4 is a longitudinal cross-sectional view through the tweezers, illustrating the adjusting mechanism in an operative position; and

Fig. 5 is a cross-sectional view on line 5—5 of Fig. 2.

Referring in detail to the present drawing there is shown tweezers, including a pair of jaws 10, the ends of which are flattened as at 11 and connected at their outer termination as at 12. Those flat ends 11 of jaws 10 are of resilient, springy nature for normally maintaining the opposite ends of jaws 10 in a separated open position, as is seen in Figs. 2 and 3. Each of said jaws 10 is

5 of substantially semi-annular formation as is clearly shown in Fig. 5, so that when jaws 10 are manually pressed towards each other, the jaws close, their opposite edges contact and the jaws 10 assume substantially cylindrical formation on transverse cross-section. The outer ends of each of said jaws 10 gradually taper, the outer free ends whereof assume sharp points 13, by means of which objects to be lifted are grasped when manual pressure is applied against the body portion of said jaws 10. The above is the usual construction of tweezers.

From the hereinabove description it will be seen that when a small object is grasped by the jaws 10 of tweezers, the same may be lifted as long as manual pressure is continued to be applied to the body portions of jaws 10. To drive a small screw, for instance, into engagement with any object, is rather inconvenient, because the slightest accidental release of jaws 10 from continual manual pressure, will separate the jaws and consequently the object held thereby will fall out. To obviate such a result, and for the purpose of maintaining jaws 10 in a continued, adjusted, frictional engagement with the object held by said jaws, the present device was made.

Said device includes staple plate 14, including angularly and transversely disposed legs 15, projecting from each end of said staple plate 14. 20 Leaves 16, laterally extending from said legs 15 and into opposite directions, constitute means for rigidly affixing said staple plate 14 to the inner periphery of one of said jaws 10. It is observed that leg 15, nearest to the inner ends of said jaws 10 is longer than the opposite leg 15, causing the body portion of said staple plate 14 to remain in an oblique position with relation to jaws 10. Said staple plate 14 is however in an oblong relation with said jaws 10. The body portion of said staple plate 14 is longitudinally and centrally slotted for defining recess 17 which is coextensive with the body portion of said staple plate 14.

Extended through said recess 17 is arm 18, rigidly formed with knob 19, of an oblong formation, arcuate on transverse cross-section, and contacting with the outer periphery of opposite jaw 10, as is clearly seen in Fig. 5. The outer face of said knob 19 is knurled, facilitating manual shifting thereof and longitudinally of said last named jaw 10.

The inner, free end of said arm 18 carries pin 20, driven through said arm 18, and in a rigid transverse relation therewith.

Said arm 18 passes through a longitudinal slot

21 made in said last named jaw 10 adjacent its inner end.

Said pin 20 normally contacts the underface of the body portion of said staple plate 14.

From the hereinabove description it will be seen that two jaws 10 are interconnected through the medium of staple plate 14 on one hand, and through the medium of arm 18 and pin 20 on the other. When knob 19 remains in the position adjacent the inner end of jaw 10 with which the same cooperates, pin 20 is adjacent the corner defined by the body portion of said staple plate 14 and the longer leg 15, thereby permitting the free ends of jaws 10 to remain open, as is seen in Figs. 2 and 3. When said knob 19 is shifted into the opposite direction, that is towards the free ends of said jaws 10, pin 20 will ride upon the lower face of the body portion of staple plate 14, and towards shorter leg 15, thereby gradually bringing the free ends of jaws 10 towards each other, until the free ends of said jaws 10 close, when arm 18 is within the opposite end of slot 21.

From the hereinabove description it will be seen that when an object is grasped by points 13 of jaws 10, manual shifting of knob 19 towards said points 13, as far as said knob 19 will go, will interlock jaws 10, thereby locking said jaws 10 against the object held therebetween, permitting free manipulation of the tweezers with the object held thereby, without fear that the object held will be disengaged from jaws 10. On shifting of knob 19 into the opposite direction, that is towards the inner ends of jaws 10, the same will release said jaws 10 from their engagement with the object held thereby.

Knob 19 is provided with a laterally extending pointer 22, on one side thereof, to cooperate with scale 23 representing fractions of an inch. If it is assumed that pointer 22, in Figs. 1 and 2, points to $\frac{1}{16}$ of an inch, indicating that points 13 of jaws 10 are separated to the extent of $\frac{1}{16}$ of an inch. From that mark scale 23 represents smaller fractions of an inch, as for instance $\frac{1}{16}$, $\frac{1}{8}$, $\frac{1}{4}$ and zero. Zero of course will be the last point on scale 23 towards the free ends of jaws 10, indicating that when knob 19 has been shifted fully towards the free ends of jaws 10, pointer 22 will point to zero indicating points 13 of jaws 10 in contact. Thus it will be seen that shifting of knob 19, along scale 23 will indicate the distance in fractional inches of points 13 of jaws 10, thereby permitting measuring of thicknesses, lengths and diameters of small objects. For instance, if a screw-head is grasped between points 13 of jaws 10, and knob 19 is shifted towards the free ends of jaws 10, as far as it will go, with pointer 22 stopping at $\frac{1}{16}$ on scale 23, it will indicate that the screwhead is $\frac{1}{16}$ of an inch in diameter.

It is observed that since the shorter leg 15 is farther removed from opposite jaw 10 than the longer leg 15, thereby the end of staple plate 14 adjacent the free ends of jaws 10 being in a nearer proximity to the jaw to which the same is attached, than the opposite end of said staple plate 14, it follows that when pin 20 is shifted towards said shorter leg 15, it draws staple plate 14, and consequently jaw 10 to which the same is attached, towards jaw 10 with which said arm 18 is in engagement through knob 19, thereby bring-

ing points 13 towards each other, and maintaining jaws 10 in their mutual, rigid adjusted relation.

While there is described herein a preferred embodiment of the present invention, it is nevertheless to be understood that minor changes may be made therein without departing from the spirit and scope of the invention as claimed.

What I claim as new is:

10 1. A tweezer comprising a pair of oppositely disposed, resilient jaws connected together adjacent one of their respective ends, the other ends thereof being free and being biased for movement away from each other, a plate rigidly secured to one of said jaws, said plate extending longitudinally of said one jaw and having a portion thereof spaced from said one jaw, said portion of said plate being inclined to said one jaw in the direction of the longitudinal axis of said last named jaw, the other of said jaws having an elongated, longitudinally extending slot formed therein, a member slidably mounted on said other jaw and having an extension thereof projecting through said slot, said extension engaging said inclined portion of said plate on the face adjacent said one jaw, whereby actuation of said member in one direction will move the free ends of said jaws toward each other against said bias, and movement of said member in the opposite direction permits the free ends of said jaws to move away from each other under the influence of said bias.

20 2. A tweezer comprising a pair of oppositely disposed, resilient jaws connected together adjacent one of their respective ends, the other ends of said jaws being free and being biased for movement away from each other, a plate rigidly secured to one of said jaws and having an elongated portion intermediate the ends thereof extending longitudinally with respect to said one jaw, said intermediate portion being inclined to said plate and having a slot formed therein extending longitudinally thereof, the other of said jaws having a slot formed therein aligned with said first slot, a member slidably mounted on the other of said jaws and having an extension thereof extending through said aligned slots, a pin extending transversely of said intermediate portion and the slot formed therein, said pin being rigidly secured to said extension, and said pin slidably engaging said intermediate portion on the face adjacent said one jaw, whereby actuation of said member in one direction will move the free ends of said jaws toward each other against said bias, and movement of said member in the opposite direction permits the free ends of said jaws to move away from each other under the influence of said bias.

JOSEPH DRABIK.
